TROUSERS

Alvin J. Wenzel, Overland Park, Kans., assignor to The H. D. Lee Company, Incorporated, Kansas City, Mo., a corporation of Kansas

Filed Aug. 23, 1963, Ser. No. 76,340

Term of patent 14 years

(Cl. D3—17)

FIG. 1 is a front view of a pair of trousers showing my new design;

FIG. 2 is a rear view thereof with the lower portion shown broken away for convenience of illustration; and FIG. 3 is a side view thereof.

I claim:

The ornamental design for trousers, as shown and described.
